UNITED STATES PATENT OFFICE.

JULIAN KENNEDY, OF LATROBE, AND HENRY AIKEN, OF HOMESTEAD,
PENNSYLVANIA.

ROLLING-MILL.

SPECIFICATION forming part of Letters Patent No. 412,852, dated October 15, 1889.

Application filed April 20, 1889. Serial No. 307,948. (No model.)

To all whom it may concern:

Be it known that we, JULIAN KENNEDY, of Latrobe, in the county of Westmoreland, and HENRY AIKEN, of Homestead, in the county 5 of Allegheny, and State of Pennsylvania, have invented a new and useful Improvement in Rolls, of which the following is a full, clear, and exact description, reference being had to the accompanying drawings, forming part of 10 this specification, in which—

Figure 1 is an end view of our improved mill. Fig. 2 is a front view thereof, the housings on one side of the mill being shown in vertical section. Fig. 3 is a sectional plan 15 view of the mill, the section being on the line III III of Fig. 2. Fig. 4 is an end view of the housings. Fig. 5 is an irregular horizontal section on the line V V of Fig. 4.

Like symbols of reference indicate like parts 20 in each.

Our invention relates to an improvement in universal mills, designed particularly for use in the rolling of flanged beams—such as I-beams, channel-beams, and the like; and it 25 consists in certain new forms of construction and combinations of the parts, which are described in this specification, and are particularly indicated in the claims.

Referring to the drawings, the mill has two 30 horizontal formative rolls 1 2 and two vertical rolls 3 3, all arranged with their axes in substantially the same vertical plane, and all driven by a suitable reversible engine. (Not shown.) The necks of the vertical rolls are 35 journaled in side frames or carriers 4, composed of strong castings, the inner parts of which are shaped to receive the necks of the rolls, which are held in place in their bearings by caps b^2 , bolted to the carriers, as shown 40 in Figs. 2 and 3. The carriers are suitably flanged and recessed, as shown in these figures, to possess the proper degree of strength, and are set in lateral wings b , which project 45 from the horizontal roll-housings and form boxes or auxiliary housings, at the bases of which the carriers are supported by guide-ways or flanges b' . At the end of each of the wings b is an end frame or plate 6, through 50 which pass adjusting-screws 7, the ends of which bear on the carrier, and which are connected with each other by gear-wheels 9 and

an intermediate gear-wheel 10. The gear-wheels 9 are fitted on the screws 7 by feather-and-spline connections, and are held in place by a face-plate 11, as shown in Fig. 1. The 55 manner of driving them will be explained hereinafter in describing the adjustment of the horizontal rolls. Each of the vertical roll-carriers is also preferably provided with a hydraulic cylinder 12, which exerts a continuous force, tending to draw it outward, thus holding it firmly against the ends of the adjusting-screws and preventing loose motion.

The necks of the vertical rolls 3 project below the carriers 4, and are provided with bevelled pinions 13 in gear with pinions 14, which are mounted on a horizontal shaft 15 by a feather and spline 16, and are connected with the carriers 4 by straps 17, having at their lower ends forks or boxes which loosely encircle cylindrical necks on the pinions and bear against collars b^3 thereon. When thus arranged, the rotation of the shaft 15 drives the rolls 3 through the pinions 13 and 14, and by reason of the fact that the pinions are 75 carried by the straps 17 in the adjustment of the carriers they are kept constantly in gear.

The bearings of the lower horizontal roll are not fixed in the housings, but are set in place therein, so that the face of the roll shall 80 rest upon and be supported by the horizontal roll 18, which is fixed to the shaft 15, and is journaled in stationary or non-adjustable bearings at the base of the housings. The upper horizontal formative roll 1 is set in the 85 housings so that its bearings shall be vertically movable therein, as hereinafter described, and above it is a horizontal driving-roll 19, which rests upon and is upheld by the roll 1, while its necks are provided with 90 bearings 20, interposed between the necks and the lower ends of vertical adjusting-screws 21.

The manner in which the horizontal rolls are journaled in the housings is as follows: 95 Interposed between the housings, near the base thereof, are two separators 22, each of which consists of a tubular portion c and two laterally-projecting wings or bars d . The bearings 23 of the roll 2 are interposed between the opposite ends of the wings d , and the separators are secured to the housings by 100

bolts 24. For convenience in making and placing the separators, the tubular portion *c* of each is preferably divided transversely into two parts. The upper portions of the 5 housings are provided with similar separators arranged in like manner, and the bearings 38 of the upper roll 1 are set in the space between the ends of the wings *d*, so as to be vertically movable therein. The bearings of 10 this roll are provided with upwardly-projecting lugs 25, to which are secured the ends of hangers or yokes 26, which extend around the necks of the roll 19, and at their upper ends are connected to a cross-head 27, Fig. 2, suspended 15 from the end of the plunger 28 of a hydraulic cylinder 29. The cylinder and plunger serve as a counter-balance, though obviously a suitable gravity counter-balance may be substituted therefor. It follows from 20 this construction that the roll 1 is suspended from the plunger 28 by means of the cross-head and the hangers, and that the weight of the driving-roll 19 is supported by the periphery of the roll 1, so that if the screws 21 be raised to permit the plunger to have free 25 vertical action it will lift the roll 1 and the upper roll 19. In practice we prefer to employ hydraulic power constantly tending to raise the plunger, so that the periphery of the 30 roll 1 is continually in contact with that of the driving-roll, and to adjust the roll 1 vertically in its bearings between the ends of the separators it is necessary only to operate the adjusting-screws, since by raising these 35 screws the hydraulic cylinder will raise the roll, and by depressing the screws the roll will be forced down thereby against the power of the cylinder. The necks of the rolls 1 and 2 are very short, the rolls being driven not by 40 individual driving-shafts, but by frictional contact with the outer rolls 18 and 19, the roll 18 being driven by the shaft 15 and the roll 19 being driven by a spindle 30, connected therewith by a coupling-box 31, as 45 shown by dotted lines in Fig. 2.

In the use of the mill for rolling beams the metal slab or bloom B is placed between the rolls, as shown in Fig. 2, and is passed back and forth between them repeatedly, the upper horizontal roll and the vertical rolls meanwhile being forced inwardly by their adjusting mechanism until the beam, with its flanges, is brought to the desired form. The number 50 of passes will vary according to the size of the slab or bloom, the condition of the metal, and the character of the beam to be made. During the reduction of the beam the stress 55 of the work is taken up by the outer driving and supporting rolls 18 and 19.

The rolls 1 and 2 are designed to be easily 60 removable from the housings and replaced by other rolls for rolling different sizes of beams, the vertical rolls serving for any size without change. In effecting such substitution the 65 carriers of the vertical rolls are first drawn back, the roll 1 is elevated above the upper

separators, and when its bearings are detached from the hangers it may be removed from the housings, the roll 19 being first blocked or jacked up in any suitable way. 70 The roll 2 is then raised until its necks are opposite the opening between the upper and lower separators, and is withdrawn through said opening. In this way the rolls may be changed in a short space of time without removing the driving-rolls or dismantling the 75 housings, and as the short-necked rolls are set entirely within the limits of the space between the upright housings it is not necessary to weaken the latter by forming any special gaps or windows therein. This is a very desirable feature of our improvement, and we intend to claim it broadly.

It remains to describe in detail the adjusting mechanism of the horizontal rolls and of 80 the vertical rolls. Each of the gear-wheels 10, forming part of the adjusting mechanism of the vertical rolls, is connected by gearing 32 with a vertical shaft 33, at the upper end of which is a pinion 34 in gear with a pinion 35 85 on a horizontal shaft 36, which is driven by belt-pulleys 37, connected with the shaft by a clutch, by means of which the shaft may be rotated in either direction, as will be readily understood. The vertical shafts 33 are also 90 connected by gear-wheels 39 39' with pinions 40, fitted on the adjusting-screws 21, with feather and spline, and connected with the top of the housings by means of split collars 41, having internal annular tongues, which fit in 95 peripheral grooves on the exteriors of the gear-wheels. It follows from this construction that driving the gear-wheels in either direction from the shaft 36 will produce motion 100 of the adjusting mechanism both of the vertical and horizontal rolls, which will therefore be adjusted simultaneously and in equal or proportional degrees.

By moving the bearings of the pinion 39 so as to disconnect it from the pinion 39' the 110 latter may be removed and replaced with a pinion of different size, so as to vary the relative rates of adjustment of the vertical and horizontal rolls. In Fig. 3 we show the bearings of the pinion 39 set in a circular groove, 115 in which they are movable around the center of the pinion 41 for this purpose. Any other suitable mechanical appliance for effecting this result may be employed.

The advantages of our invention will be 120 appreciated by those skilled in the art. The mill is simple and strong in its construction, efficient in its action, and by reason of the facility with which the rolls may be removed and replaced by others of different shape and 125 size of working-face beams of different sizes and forms may be rolled in the mill with loss of but little time.

The mill may be modified in many ways 130 in details of construction by the skilled mechanic without involving a departure from the principles of our invention as stated in

the following claims, each of which states an item of invention unlimited by the qualifications and limitations stated in other claims.

We claim—

- 5 1. The combination of a forming-roll, an upper driving-roll upheld thereby, and a counter-balance supporting the bearings of the forming-roll, substantially as and for the purposes described.
- 10 2. The combination of a forming-roll, an upper driving-roll upheld thereby, a counter-balance, and hangers encircling the necks of the driving-roll and connected with the bearings of the forming-roll, substantially as and for the purposes described.
- 15 3. The combination of a forming-roll, an upper driving-roll upheld thereby, a counter-balance supporting the bearings of the forming-roll, and adjusting-screws for the driving-roll, substantially as and for the purposes described.
- 20 4. In a universal mill, the combination of vertical rolls, short-necked horizontal rolls, outer driving-rolls, and a counter-balance, connected with the bearings of the upper short-necked roll, and supporting it, together with the driving-roll, substantially as and for the purposes described.
- 25 5. The combination of a forming-roll, an upper driving-roll upheld thereby, a counter-balance, a cross-head 27, and hangers encircling the necks of the driving-roll and connected with the bearings of the forming-roll, substantially as and for the purposes described.
- 30 6. The combination, with the housings and the rolls, of separators interposed between the housings and having between them the bearings of the rolls, substantially as and for the purposes described.
- 35 7. The combination, with the housings and the rolls, of separators interposed between the housings and having between them the bearings of the rolls, and bolts passing through

the separators and housings, substantially as and for the purposes described.

8. In a universal mill, the combination of the horizontal roll-housings, side rolls and their carriers, and wings projecting from the sides of the housings, in which the said carriers are movably supported, substantially as and for the purposes described.

9. In a universal mill, the combination, with the horizontal rolls and side rolls and their adjusting-screws, of common driving mechanism which actuates the adjusting-screws of both horizontal and side rolls, and means whereby the relative speed of said adjusting-screws may be varied, substantially as and for the purposes described.

10. The combination, with the adjusting-screws 21, of a pinion 40, connected therewith by a traveling connection—such as a feather and spline—and a divided collar, by which the pinion is held to the housing, substantially as and for the purposes described.

11. The combination, with the upright housings, of forming-rolls—such as the rolls 1 and 2—having their necks entirely within the space between the housings, and vertical bars 70 or wings d, between which the necks of the rolls are set, substantially as and for the purposes described.

12. The combination, with the peripherally beveled or shaped forming and reducing rolls—such as the rolls 1 and 2—one at least of which is frictionally driven, of an outer roll, against which the face of such forming and reducing roll has a bearing, and by which it is frictionally driven, substantially as and for the purposes described.

In testimony whereof we have hereunto set our hands this 13th day of April, A. D. 1889.

JULIAN KENNEDY.
HENRY AIKEN.
